UNITED STATES PATENT OFFICE.

EARL S. WALLEN, OF LANSFORD, PENNSYLVANIA, ASSIGNOR, BY MESNE ASSIGNMENTS, TO COXE TRAVELING GRATE COMPANY, OF HAZLETON, PENNSYLVANIA, A CORPORATION OF PENNSYLVANIA.

MECHANICAL STOKER.

1,339,531.

Specification of Letters Patent. Patented May 11, 1920.

Application filed October 8, 1917. Serial No. 195,412.

To all whom it may concern:

Be it known that I, EARL S. WALLEN, a citizen of the United States, residing at Lansford, in the county of Carbon and State 5 of Pennsylvania, have invented certain new and useful Improvements in Mechanical Stokers; and I do declare the following to be a full, clear, and exact description of the invention, such as will enable others skilled 10 in the art to which it appertains to make and use the same.

My invention relates to improvements in mechanical stokers and more particularly to that type employing a traveling grate and 15 means for forcing air pressure upwardly therethrough, and the object is to provide simple and inexpensive means to prevent the leakage of air pressure around the ends of 20 the grate bars. This leakage has heretofore blown the powdered coal or the like away from the side walls of the firebox and caused the fire to be poor along the sides, and the 25 excess draft at this point has been found to fuse clinkers to the brickwork, thus lowering the efficiency of the furnace greatly. Fine coal also falls down through the grate 30 bars onto the chain rail and the escaping air pressure blows this coal out of the front of the furnace onto the floor, thus meaning the continual expenditure of time and labor 35 in removing this leakage.

With the foregoing general object in view, the invention resides in certain novel features of construction and unique combinations 40 of parts to be hereinafter fully described and claimed, the descriptive matter being supplemented by the accompanying drawings which form a part of this specification and in which:

Figure 1 is a longitudinal section of a stoker embodying the improved features of 45 construction;

Fig. 2 is a horizontal section showing a top plan view of a portion of the traveling 50 grate;

Fig. 3 is a vertical transverse section on the plane of the line 3—3 of Fig. 1;

Fig. 4 is an enlarged top plan of one end 55 of a pair of the grate bars, showing more particularly the arrangement of air sealing webs thereon;

Fig. 5 is a transverse section of one of the grate bars on the plane of the line 5—5 of Fig. 4; and,

Fig. 6 is a perspective view of one end of 55 one of the grate bars.

In the drawings above briefly described, the numeral 1 designates a firebox whose bottom is formed by a traveling grate 2, said grate including a pair of side chains 3 and 60 transverse grate bars 4 joined at their ends to said chains, the usual chain rails 5 being provided for supporting said chains as they travel between the drums 6 at the front and rear of the furnace. Fuel such as slack is 65 fed to the traveling grate 2 through a hopper 7 at the front end of the furnace and air pressure is supplied beneath the upper reach of said grate by any preferred means such as the usual wind box 8 having the 70 well known air connections 9.

As above stated, considerable leakage of air has heretofore occurred around the ends of the grate bars 4, it being the intention of the present improvements to check this 75 leakage in so far as possible. To this end, I provide seal plate means consisting of a pair of longitudinal plates or ledges 10 which extend inwardly beyond the chain rails 5, and equip the grate bars 4 with outer 80 and inner air sealing ribs or webs 11 and 12 respectively which travel on said ledges as shown clearly in the drawings. By this arrangement, any air leaking past the inner webs 12 will be checked by the outer webs 85 11 and will thus be given a chance to rise through the grate bars rather than leaking past said webs 11 and around the ends of the bars. I have found by this arrangement, that the leakage of air around the ends of 90 the grate bars is so reduced as to positively prevent all of the undesirable results above enumerated.

The outer webs 11 which extend transversely of the grate bars 4, have their opposite ends offset laterally, so that the several webs will overlap as shown clearly in Fig. 2. One end of each web 11 extends beyond one edge of the grate bars, whereas the other end thereof terminates flush with the 95 opposite edge of said bars, the latter being provided with vertical notches or sockets 13 so that the projecting ends of each web 11 will be received in the socket 13 of the adjacent grate bar. By this arrangement, it 100 is practically impossible for the air to leak past the several webs, even though a slight amount of this air should pass the webs 12.

The last named webs extend beyond the grate bars at one end, whereas their other ends are formed with vertical notches or sockets 14, the projecting ends of said webs being received in the sockets of the adjacent grate bars as illustrated in Fig. 2, so that an effective air seal is provided. The projecting ends of the webs 11 and 12 are disposed in vertical planes as shown clearly at the left 10 of Fig. 5, but in order that the grate bars may properly angle when the grate passes around the drums 6, the inner walls of the sockets 13 and 14 diverge downwardly from said ends. This is shown most clearly at 15 the right of Fig. 5 and in Fig. 6.

The usual keys 15 are dovetailed at 16 upon the grate bars 4 in the well known manner, the lower sides of said keys having the usual grooves 17 which extend transversely of the line of travel of the conveyer or grate; and in order to seal these grooves to prevent air from leaking therethrough above the ribs 12, the upper edges of said ribs are provided with upstanding projections 18 which are snugly received in the grooves as disclosed in Fig. 1. If desired, the webs 11 may also be provided with projections such as those indicated at 19, but in most cases this is unnecessary since the end 30 most keys abut the chain 3 and thus prevent the leakage of air excessively at this point.

From the foregoing, taken in connection with the accompanying drawings, it will be obvious that although my invention is of 35 extremely simple and inexpensive nature, it will be highly efficient and durable for the purposes intended, that is for preventing the leakage of air around the ends of the grate bars. Since probably the best results are 40 obtained from the specific construction shown and described, this construction constitutes the preferred embodiment of the device. I wish it understood that within the scope of the invention as claimed, numerous minor changes may well be made 45 without sacrificing the principal advantages.

I claim:

1. In a mechanical stoker, the combination of a firebox, a traveling grate forming the 50 bottom of said firebox and including side chains and transverse grate bars supported thereby, and ledges upon which the ends of said grate bars slide, said grate bars being provided at their ends with transverse air sealing webs contacting with said ledges, and with additional transverse air sealing 55

webs spaced inwardly from said first named webs and also contacting with said ledges.

2. In a mechanical stoker, the combination or a firebox, a traveling grate forming the 60 bottom of said firebox and including side chains and transverse grate bars supported thereby, and ledges upon which the ends of said grate bars slide, said grate bars being provided at their ends with transverse air 65 sealing webs contacting with said ledges, one end of each web extending laterally from one edge of the grate bar, whereas the opposite edge of the bar is provided with a vertical notch, the projecting ends of the 70 several webs being received in the notches of adjacent grate bars, said grate bars also having additional transverse air sealing webs spaced inwardly from said first named webs, said additional webs being disposed in sliding contact with said ledges and having one end extending beyond one side of the grate bars, whereas the other ends of said webs are each formed with a vertical notch, the projecting ends of said last named webs being 75 received in the notches of the adjacent webs, substantially as and for the purpose specified.

3. In a mechanical stoker, the combination of a firebox, a traveling grate forming 85 the bottom of said firebox and including side chains and transverse grate bars supported thereby, keys on said grate bars having the usual grooves in their inner faces, and ledges upon which the ends of the grate bars slide, 90 said grate bars being provided at their ends with transverse air sealing webs contacting with said ledges and with additional transverse air sealing webs spaced inwardly from said first named webs and also contacting 95 with said ledges, the upper edges of said additional webs having projections extending into and sealing said grooves.

4. In combination with a traveling grate, a wind box subjacent the working portion 100 of the grate, seal plate means at the sides of the wind box and closely spaced sealing ribs at the sides of the grate coöperating with said plate means to afford a double seal at the side margins of the grate. 105

In testimony whereof I have hereunto set my hand in the presence of two subscribing witnesses.

EARL S. WALLEN.
